GUN BOLT

Sigmund Schiff, Cincinnati, Ohio

Application December 5, 1945, Serial No. 633,031

5 Claims. (Cl. 89—191)

(Granted under the act of March 3, 1883, as
amended April 30, 1928; 370 O. G. 757)

1

The invention described herein may be manufactured and used by or for the Government for governmental purposes without the payments to me of any royalty thereon.

This invention relates to an improved construction of bolt for use with 20 mm. aircraft automatic guns.

It is the primary object of this invention to provide an improved construction of bolt for use with the above mentioned type gun and which is of a greatly simplified construction and design as compared to the bolt now employed in the 20 mm. gun; and by means of which many of the parts of the conventional bolt are eliminated to thus provide a bolt which is more efficient and faster in operation, and which is considerably more durable through the elimination of many small parts which are especially subject to breakage.

More particularly, it is an object of the invention to provide an improved construction of bolt of the type operated by a combination of forces including gas recoil means and blowback means; which is formed of two primary sections having a limited relative movement for unlocking the bolt after firing to permit recoil of the bolt with accompanying extraction, ejection and feeding of the ammunition; and which is provided with novel means which, upon counter-recoil movement, initially locks one section of the bolt in battery position and thereafter permits forward movement of another section of the bolt for projecting the firing pin to explode the chambered round to cause the cycle of operation of the piece to be repeated.

Other objects and advantages of the invention will hereinafter become more fully apparent from the following description of the drawings, which illustrates a preferred embodiment of the invention, and wherein:

Figure 1 is a fragmentary longitudinal sectional view, partly in side elevation, of a portion of a 20 mm. aircraft gun and with the improved bolt shown locked therein in battery position;

Figure 2 is a similar view showing the bolt held in a retracted, cocked position;

Figure 3 is a view similar to Figure 1 showing the initial movement of one section of the bolt, relatively to the other section thereof, and constituting the first stage of the bolt recoil; and

Figure 4 and 5 are cross sectional views on enlarged scales taken substantially along the planes as indicated by the lines 4—4 and 5—5, respectively, of Figure 1.

Referring more particularly to the drawings, wherein like reference characters designate like or corresponding parts throughout the several views, 6 designates generally a portion of the receiver of a 20 mm. antiaircraft automatic gun of the M2 series, which is of conventional con-

2

struction except for the belt, designated generally 7, and which comprises the invention.

Only so much of the receiver and other associated parts have been illustrated as are necessary to illustrate the application of the bolt 7.

The bolt 7, as previously mentioned, is actuated in recoil initially by a gas operated piston and thereafter by blowback force. The piston, not shown, obtains impetus from a portion of the propelling gases from the bore 8 of the barrel 9 through a port, not shown, to drive a sleeve 10 rearwardly. Sleeve 10 is connected at its forward end to the piston. The rear end of the sleeves 10 is shown in Figure 1, and said rear end terminates in a yoke, not shown, which drives push rods 10a rearward, which, in turn, strikes portions of the bolt 7 for driving a part of the bolt rearwardly to initiate its recoil movement. The push rods 10a are shown in dotted lines in Figure 4 and are reciprocally mounted in receiver 6 lengthwise thereof. The forward ends of push rods 10a protrude from the forward end of receiver 6 into the path of rearward movement of the yoke. The sleeve 10 is thereafter returned to a forward, inoperative position by an extension spring 11.

The bolt 7 includes a lower section or breechblock, designated generally 12, and an upper section or breechblock slide, designated generally 13. As best seen in Figures 4 and 5, the receiver 6 is provided with an upper chamber 14 in which the bolt 7 is reciprocally mounted and the lower portion of the receiver 6 is provided with rails 15 for slidably supporting the bolt 7.

The upper surface of the breechblock 12 is provided with recessed faces 16 at the sides thereof, and the underside of the breechblock slide 13 is provided with depending sides or shoulders 17 for engaging the faces 16 and for providing a connection between the bolt sections 12 and 13 to permit relative lengthwise sliding movement, but which prevent any lateral movement of the connected sections. Axially of the bolt 7, the sections 12 and 13 are provided with complementary recesses which extend from adjacent the forward end of the bolt 7 and which open outwardly of the rear end thereof to form a bore 18 in which a firing pin 19 is slidably mounted lengthwise of the bolt 7.

As best seen in Figure 1, a driving spring guide plunger 20, formed of telescoping sections, has one end thereof extending through the bore 18 and terminating in the head 21 which bears against the rear end of the firing pin 19. The opposite end of the guide plunger 20, not shown, bears against the buffer assembly, not shown, and likewise is provided with a headed end. The guide plunger 20 carries a driving or counter-recoil spring 22, the ends of which bear against the headed ends of the plunger 20 for urging the firing pin 19 and the bolt 7 forward of the re-

ceiver 6. As best seen in Figure 1, firing pin 19 is provided with a body portion which is circular in cross section and which is stepped intermediate of its ends to form a forwardly facing shoulder 23 which bears against a rearwardly facing shoulder 24 on the breechblock slide 13. The breechblock 12, at its forward end, is provided with an upstanding wall 26 the forward side of which forms the bolt face and which is provided with an axially arranged opening 27 to receive the tapered forward end 28 of the firing pin 19, which projects therethrough and beyond the face of the bolt, when the firing pin 19 is in its forwardmost position, as seen in Figure 1, for exploding a round of ammunition, not shown, contained in the chamber 29 of the rifle bore 8. The rear side of wall 26 forms an abutment for an annular forwardly facing shoulder 25, formed by the tapered part 28, and against which the firing pin bears when bolt 7 is in battery position, as seen in Figure 1. The bolt 7 is provided with an extractor 30, carried by the breechblock 12 in a conventional manner.

The breechblock slide 13, as seen in Figures 4 and 5, is provided with corresponding vertically enlarged side portions 30, of which the shoulders 17 form the lower portions. Sides 30, intermediate of the ends of the slide 13, are provided with downwardly and outwardly opening recesses 31 through each of which extend a guide rod 32. The guide rods 32 are suitably anchored at their ends in portions of the slide 13 and mount expansion springs 33 which are carried thereby. A lug 34 is slidably mounted on each of the guide rods 32. The rear ends of the springs 33 bear against the forward ends of the lugs 34 for urging said lugs rearwardly. A plate 35 is secured to each side of the slide 13 by screw fastenings 36, and said plates are provided with inturned lower ends, as seen in Figure 4, which combine with portions of the perpendicular parts of the plates 35 to form housings for inclosing the rods 32 and the springs 33. As seen in Figure 1, the inturned portions of the plates 35 are cut out, at the rear ends thereof, to form openings 37 through which project the depending extensions 38 of the lugs 34. The sides of the breechblock 12 are provided with upwardly opening notches 39 to receive the extensions 38 for yieldably connecting the bolt sections 12 and 13.

The breechblock 12, adjacent its rear end, and at the bottom thereof, is provided with a rearwardly facing shoulder having a rearwardly directed arcuately shaped groove 40 which extends transversely thereof. A breechblock lock 41 is mounted in the recessed underside 42 of the breechblock 12, behind the rearwardly facing shoulder, and is provided with a rounded forward end 43 which is pivotally mounted in the recess 40. The receiver 6 is provided with a transversely disposed, fixed breechblock key 44 having an upwardly and forwardly facing, transversely extending notch 45 to receive the lower, rear end of the breechblock lock 41, when the breechblock 12 is in a battery position, as seen in Figure 1. The slide 13, adjacent its rear end, is provided with downwardly opening notches 46, at the sides thereof, to receive the upwardly and forwardly inclined projections 47 which project from the lock 41, adjacent the side edges thereof. The notches 46 are provided with rearwardly facing upwardly and forwardly inclined cam faces 48, at their forward ends for engagement with the upwardly and forwardly inclined forward faces 49 of the extensions 47, and the notches 46 are also provided

with the forwardly facing inclined faces 50 at their rear ends which coact with the rearwardly facing correspondingly inclined faces 51 of the extensions 47, as will hereinafter be described.

The lock 41 is recessed in its underside to form a latch face 52 to engage a sear 53, in a conventional manner, when the bolt 7 is in a fully retracted position, as seen in Figure 2. The lock 41 is also provided with forwardly facing upwardly and rearwardly inclined cam surfaces 54, at the sides thereof, for engagement with the cam surfaces 55 which are rigidly secured to the sides of the receiver 6, as best illustrated in Figure 2. The forwardly facing, upwardly extending side of the notch 45 is inclined rearwardly to provide a cam engagement with the similarly inclined rear end portion 56 of the lock 41.

The side portions 30 extend to the forward end of the breechblock slide 13 and are disposed just behind and at the sides of the breechblock portion 26 with the forward ends thereof exposed, to be engaged by push rods 10a which are reciprocally mounted in the receiver 6 and which are engaged in a conventional manner by the yoke of the sleeve 10.

Assuming the bolt 7 to be in its battery position, as seen in Figure 1, which position it assumes at the instant that the firing pin 19 strikes and explodes a round of ammunition, not shown, contained in the chamber 29 and which bears against the face of the bolt 7; as the projectile from the round of ammunition moves through the bore 8 a portion of the propelling gases thereof acts upon the piston, not shown, connected to the sleeve 10, for driving the sleeve rearwardly. This rearward movement of the sleeve 10 is imparted, through its yoke and the push rods 10a to the forward ends of the side rails 30 against which the rear ends, not shown, of push rods 10a bear. The side rails 30, forming integral parts of the breechblock slide 13, upon receiving the impact of the push rods 10a cause the slide 13 to be driven rearwardly. The breechblock 12 is held in a battery position due to the lock 41 engaging the notch 45 of the breechblock key 44, thus causing the slide 13 to move relatively to the breechblock 12. The shoulder 24 of slide 13 engaging the shoulder 23 carries the firing pin 19 rearwardly with the slide 13 and relatively to the breechblock 12, as illustrated in Figure 3, thus retracting the firing pin extension 28 out of the opening 27 and out of engagement with the cartridge case, not shown, held against the bolt face by the extractor 30'. This initial, gas produced movement of the slide 13, relatively to the breechblock 12, causes the cam surfaces 48 to engage the cam surfaces 49, as seen in Figure 3, to cam the lock 41 upwardly and out of engagement with the notch 45 and partially into the notches 46, so that the lock 41 clears the upper surface of the breechblock key 44. This unlocks the breechblock 12 permitting it to be driven rearwardly by blowback pressure and also locks the slide 13 in its retracted position to the breechblock 12. As the bolt 7 moves rearwardly against the action of the spring 22, the lock 41 is supported in its elevated position of Figure 2 by the rear sections of the rails 15. The tubular rear end portion 57 of the bolt 7 strikes the buffer plate, not shown, to terminate the recoil travel of the bolt after which the driving spring 22 begins to propel the bolt 7 forwardly in its counterrecoil movement. Midway of the recoil movement of the bolt 7, the rim of the cartridge, not shown, which has been extracted from the

chamber 29 by the extractor 30' is engaged by the horns of the ejector, one of which is shown at 58, for ejecting the empty cartridge case through the bottom of the receiver 6 in a conventional manner. If the trigger, not shown, has been released at approximately the beginning of the rearward travel of the bolt 7, the sear 53 will have assumed its position of Figure 1 and will have been cammed downwardly by the cam surface 56 during the recoil movement of the bolt 7, 10 and will thereafter have moved upwardly and into the recessed underside of the lock 41 to latch the bolt 7 in an open and cocked position, as seen in Figure 2; in which position it will be held until the trigger is again pulled to release the sear 53 from engagement with the forwardly facing shoulder 52 of lock 41. Normally, however, the trigger is held retracted to thereby hold the sear 53 out of the path of movement of the shoulder 52 so that the bolt 7 moves forwardly unobstructed under the impetus of the driving spring 22. During its forward movement the bolt face strips a new round of ammunition, not shown, from a magazine, not shown, mounted above the receiver 6, and carries the new round forwardly and chambers it as the breechblock 12 returns to its battery position. As the breechblock 12 reaches the battery position, as seen in Figure 3, the rear end of the lock 41 clears the upper surface of the breechblock key 44, allowing the rear end of the lock 41 to be cammed back into the notch 45 by the cam surfaces 54 of lock 41 engaging the cam surfaces 55 of the receiver 6, to force the lock 41 downwardly and to thereby release the slide 13 to move forward relatively to the breechblock 12. The breechblock slide 13 is thereafter driven forward, relatively to the breechblock 12, and to its forwardmost position of Figure 1 by the driving spring 22 and the springs 33, through the engagement of the extensions 38 with the notches 39, to thereby project the extension 28 of the firing pin 19 through the opening 27 for exploding the newly chambered round of ammunition and to cause the cycle of operation, which has been previously described, to be repeated.

Various modifications and changes in the construction of the bolt, forming the invention, are contemplated and may obviously be resorted to without departing from the spirit and scope of the invention as hereinafter defined by the appended claims, as only a preferred embodiment thereof has been illustrated and described.

I claim:

1. In an automatic weapon, the combination of a receiver, a breechblock reciprocally mounted therein, a breechblock slide reciprocally mounted on said breechblock, a firing pin, said breechblock and said breechblock slide having opposed complementary recesses forming a bore for receiving the firing pin for longitudinal movement therein, said breechblock slide having a limited longitudinal sliding movement relative to the breechblock, a key connected to said receiver, a lock on said breechblock adapted to engage said key for holding the breechblock in battery position, gas actuated means for moving the breechblock slide rearwardly relatively to breechblock, cam means on the lock and breechblock slide for camming the lock out of engagement with said key when the breechblock slide is moved rearwardly relatively to the breechblock, said breechblock being movable rearwardly by blowback for extracting an empty cartridge case, driving means for moving the breechblock and breechblock slide forward 75

to pick up and chamber a round of ammunition, cam means on the breechblock slide and lock for returning the lock to a locked position with said key when the breechblock reaches a battery position, to release the slide, and said driving means bearing against the firing pin to move the breechblock slide forward, relatively to the breechblock, to project the firing pin to detonate the chambered round of ammunition.

5 2. A bolt as in claim 1, said breechblock slide being disposed above the breechblock, and said breechblock having an upwardly extending forward end forming the bolt face and provided with an opening for the firing pin.

15 3. A gun bolt comprising a breechblock forming the lower section of the bolt, an upstanding wall on said breechblock and provided with an opening, a breechblock slide forming the upper section of the bolt, means attached to said 20 breechblock slide for moving the same rearwardly, and spring means connecting the breechblock and breechblock slide for limited lengthwise sliding movement of the breechblock slide relatively to the breechblock, said breechblock and

25 breechblock slide having complementary recesses forming a bore, a spring projected firing pin contained in the bore and adapted to be projected through the opening in said upstanding wall, and engaging shoulders on the breechblock slide 30 and firing pin for retracting the firing pin from the opening when the breechblock slide is moved rearwardly relatively to the breechblock.

35 4. A gun bolt as in claim 3, and a breechblock lock pivotally mounted on the breechblock, a breechblock key fixedly disposed relatively to the bolt and engaged by the breechblock lock for retaining the breechblock in battery position, interengaging cam means on the breechblock slide 40 and breechblock lock for camming the lock away from the key to a released position when the breechblock slide is moved rearwardly relatively to the breechblock.

45 5. A gun bolt formed of an upper section the said sections having opposed complementary longitudinally extending recesses forming a bore extending longitudinally of the bolt, and a lower section, a firing pin slidably mounted between said sections and lengthwise thereof in said bore, a counterrecoil spring means bearing against the firing pin and urging it forward, relatively to the bolt, said upper section being mounted on said lower section for limited reciprocating movement relatively to the lower section, said firing pin and upper section having engaging faces to cause the firing pin to move rearward with the upper section and to cause the upper section to move forward with the firing pin, means for initially moving the upper section rearwardly relatively to the lower section, for cocking the firing pin, and means for latching the upper section and the lower section in a rearward position.
